UNITED STATES PATENT OFFICE.

ALFRED WEILAND, OF PHILADELPHIA, PENNSYLVANIA.

CARBURETER.

1,005,491.

Specification of Letters Patent. Patented Oct. 10, 1911.

Application filed January 21, 1909. Serial No. 473,406.

To all whom it may concern:

Be it known that I, ALFRED WEILAND, a citizen of the United States, residing in the city and county of Philadelphia, State of Pennsylvania, have invented a new and useful Carbureter, of which the following is a specification.

This invention relates to carbureters and has for an object to supply an air and fluid mixture to an engine and so proportion the two relative one to the other as to furnish at all times and under all conditions a mixture bearing an accurate relation to the speed of the engine, that is to say under conditions of a heavy load and consequent slow speed, a mixture rich in fuel will be supplied, while in conditions of light load and high speed, a correspondingly "lean" mixture will be delivered.

In carbureters as heretofore constructed, the speed of the engine so operates upon the controlling devices comprising the carbureter that at the very time a rich mixture is desired the suction around the gasoline nozzle is so reduced as to produce a "lean" mixture, while at high speed the reverse takes place and instead of having a reduction in the percentage of fuel fluid, an increase takes place and an overrich mixture is the result. Furthermore, to overcome these difficulties in some carbureters the fluid has been controlled by mechanical devices, such as cams, rollers or the like, but their positive action cannot be depended upon at all times for regulation, since lost motion is sure to develop if not actual sticking of the parts to render them inoperative. In such carbureters also an adjustment of the throttle results in throwing other controlling parts out of adjustment and there are no means, in so far as I am aware, whereby any controlling parts may be regulated at the will of the operator without correspondingly affecting the other coöperating parts and thus seriously effecting any predetermined set action.

In my present invention I have devised a new and novel carbureter consisting of an arrangement of coöperating parts whereby the demands upon an engine are freely and accurately met by a ready response from the controlling devices operating upon the air and fuel fluid.

It consists of a carbureter having an adjustable air valve so constructed as to throw

into operation during the starting movement of the engine or at very slow speeds, two auxiliary mixture controls, whereby at such times an exceedingly rich mixture is supplied to impart an efficient working stroke to the engine.

It further consists of a throttle so arranged and controlled as to permit ready adjustment thereof without affecting adjacent coöperating parts and also allows these same parts to be independently adjusted and the relation between them changed without altering or in any way producing a change in the position of the throttle, thereby rendering complete regulation of the fluid and the mixture for any predetermined position of the main throttle.

It further consists of an auxiliary device controlling an auxiliary mixture supply and located exterior of the carbureter casing, by means of which the starting and slow speed movements of the engine may be readily controlled.

It further consists of other novel features of construction, all as will be hereinafter fully set forth.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a sectional elevation of a carbureter embodying my invention. Fig. 2 represents a section on line $x-x$, Fig. 1. Fig. 3 represents a section on line $y-y$, Fig. 1. Fig. 4 represents a section through a portion of the carbureter showing the auxiliary priming device.

100

Similar numerals of reference indicate corresponding parts in the figures.

Referring to the drawings:—1 designates a casing forming a fluid reservoir 2, inlet to which is had through a port 3, the same communicating with a valve seat 4, in the present instance cylindrical in form and having a bore 5 therein adapted to receive a valve 6. As here shown, the valve 6 is provided with suitable guide lugs 7 to prop-

110

erly position the valve within its seat and permit the flow of fluid past the said lugs into the casing 1, and has secured to the top thereof a connection 8 with which co-
5 operates a plurality of suitably pivoted levers 9. These levers are connected, at one end, to a float 10 of suitable buoyant material located within the casing 1 and adapted to rise and fall as the fluid level varies
10 therein and thus produce a movement of the valve 6 to open and close the opening to the bore 5 to admit fluid through the port 3 and to the reservoir chamber 2.

11 designates a second casing suitably
15 mounted on the casing 1 and forming therewith in a mixing chamber 12, the top of which is formed by a cover 13, the three members, cover 13, mixture casing 11 and fluid casing 1, in the present instance, being secured together by means of suitable bolts 14, whereby their removal permits ready inspection
20 of the interior of my novel carburetor. The mixture chamber casing 11 is provided with the usual outlet 15, whereby the fluid mixture is conveyed from the mixing chamber
25 12 to the engine cylinder. The bottom 16 of the casing 11 is provided, in the present instance, with a depending portion 17 forming an auxiliary reservoir 18 therein and having
30 in the bottom thereof an opening 19 permitting the fluid to flow from the reservoir 2 into the auxiliary reservoir 18. It will be noted that it is preferable to form interior
35 of this auxiliary reservoir, an extension 20 surrounding the inlet 19, whereby a seat 21 is provided, for a purpose to be later described.

22 designates a tubular member, here shown as having threaded ribs 22^x to secure
40 it to the depending portion 17 and provided also with an extension 23 conforming in shape to the contour of the bottom 16 of the casing 11 and preferably terminating in close proximity to the wall of the bottom 16,
45 whereby in the preferred form an annular opening 24 is provided. The outer edge of the extension 23 is preferably upturned, whereby a seat 25 is formed for a main air valve 26, which is connected by radial arms
50 27 to a sleeve 28, extending in the present instance exterior of the cover 13.

29 designates an opening in the cover 13 forming an air inlet and it will be apparent that when the valve 26 is raised from the
55 seat 25 that the exterior air has a free passage through the main air valve member 26 to the mixture outlet 15.

30 designates a throttle valve slidably mounted in a prolongation 31 of the cover
60 13, the said prolongation extending a short distance from the bottom of the casing 11 in order to guide the valve 30 properly into a seat 32, formed in casing 11, and yet allow free passage of air and fluid to the outlet
65 15 when the throttle 30 is open. Attention

is directed to the lower portion 30^x of the throttle valve, which in the present instance is shown tapering upwardly on one side from a point approximately the middle thereof toward the mixture outlet 15, 70 whereby when the throttle is completely closed on one side, the opposite side will be partly open and a slight lead is provided for the flow of the mixture. The throttle valve 30 is preferably formed with integral radial arms 33, which extend from a sleeve 34 slidably mounted in an opening 35 in the cover 13, the end of said sleeve having a thread 36 thereon adapted to receive an adjusting nut 37, for a purpose to be presently 80 described.

38 designates a cap suitably secured to the sleeve 28, in the present instance being threaded thereon in order to provide a means to adjust the position of the valve 26 with respect to the throttle 30. The cap 38 is provided with a series of apertures 39 suitably disposed about the circumference of the cap 38 and providing air passages leading from the exterior of the device to the interior of the sleeve 28. It will thus be apparent that exterior air may be admitted through the openings 39, traversing the sleeve 28 and tube 22, which leads it directly into the auxiliary fluid reservoir 18. The 95 cap 38 is provided with a screw threaded aperture 40 adapted to receive a plug 41 having, in the present instance, integral therewith a tube 42 extending to a point preferably below the normal level of the 100 fluid in the reservoir 18 and having apertures 43 adjacent the end, whereby an auxiliary supply of fluid may be delivered to the reservoir 18 under certain conditions.

44 designates a valve having a bore 45 105 therein and provided with an exterior taper adapted to coöperate with the valve seat 21 to control the main supply of fluid from the reservoir 2. The bore 45 is adapted to be controlled by needle valve 46, the same being adjustably mounted on the plug 41 and controlled by thumb nut 47. It will be noted that the tubular member 22 is provided with suitable passages 48 therethrough forming communication between 115 the auxiliary chamber 18 and the chamber 49 leading to the annular port 24.

It will be noted that the cap 38 normally rests upon the adjusting nut 37 and gravity thereby allows it to move with the throttle 120 valve 30 in a corresponding manner. In order to maintain correct relation between the valve 26 and the throttle 30 a spring 50 is preferably interposed between the two valves. In the present instance the throttle 125 valve 30 is controlled by a plurality of levers 51 operating in slotted portions 52 of the sleeve 34, the said cranks 51 being keyed to a shaft 53 and controlled at the will of the operator by a lever 54. Suitable lock nuts 130

55 and 56 are mounted respectively on the plug 41 and needle valve stem 46, whereby the respective parts may be held in adjusted position.

- 5 In Fig. 4 I disclose an auxiliary device controlling an auxiliary mixture supply for starting and slow speed, being located exterior of the main casing and detachably secured thereto by unions 57 having ports 10 58 and 59 therein leading respectively to the mixture chamber 12 and fluid reservoir 2. In order to accurately adjust the inlet 58, I preferably provide a valve member 58* of any suitable construction.
- 15 60 designates a tube having an inlet 61 communicating through the aperture 59 with the fluid reservoir 2 and an outlet 62 leading to the port 58 and opening into the chamber 12 or any part of the inlet passage 20 beyond the main throttle 30.
- 63 designates a tube having needle valve extremity 64 adapted to operate with the inlet opening 61 and adjacent which are a plurality of openings 65 communicating 25 with the bore 66 of the tube, whereby exterior air is introduced beneath the liquid in the tube 60. In the present instance the tube 63 is screw threaded into the tube 60 and in order to allow an adjustment of the 30 valve 64 a nut 67 is provided in order to lock the parts in adjusted position.

It will be apparent by this device that a very rich mixture may be delivered to the engine without opening the main air valve, 35 since as soon as the engine is cranked a vacuum is created within the mixing chamber and its outlet, sufficient to draw in a quantity of air through the bore 66 and deliver the same through the aperture 65 beneath the surface of the fluid, thereby directly supplying a mixture rich in fuel.

The operation of the device is as follows:—The carbureter having been properly adjusted and connected, a supply of fluid 45 enters through the inlet 3 and as the float 10 at this time is in its lowest position, the valve 6 will be open and permit an unrestricted flow through the passage 5 to the reservoir 2 in which it ascends and gradually raises the float until the desired height 50 has been reached, when the valve 6 will be operated through the levers 9 and cut off the further entrance of fluid. The relation between the float and the valve operating 55 mechanism 8 and 9 is so adjusted as to allow the fluid in the reservoir 2 to normally rise to a level sufficiently high to fill both the auxiliary reservoirs 18 and 60 to the desired level. In the starting and slow speed position 60 of the carbureter the controlling valves are in the position indicated in dotted lines in Fig. 1 and it will be noted that the throttle valve 30, owing to the tapering portion thereof is slightly open at one side to provide an exit for the mixture which has

passed through annular opening 24 at starting and slow speed, when the main air valve 26 is closed altogether. In bringing the carbureter into action the throttle valve 30 is slightly open, leaving the main air valve 26 still closed upon its seat 25 and thereupon preventing any air entering the mixing chamber from the inlet 29, so that all the air which enters the carbureter does so by way of the auxiliary starting devices, before described, from which it passes out beneath the fluid in the reservoirs 18 and 60 and exits through openings 48 and 62 rich in fluid fuel, passing to the mixing chamber and engine inlet.

Attention is called to the proportion of the port 24, since it is advisable for best results, to make the same smaller than the smallest area of the supplemental air inlet tube 28 or "equalizer" tube, as I term it, in order that any suction produced in the reservoir 18 may be equalized by the air entering from the outside. The work of the equalizer and external auxiliary carbureter having been performed in the starting operation, the throttle valve 30 is further opened and raises the valve 26 from its seat, since it is supported loosely on the top thereof, whereupon air is permitted free passage through the opening 29 and valve 26, mixing with the overrich discharge from the annular port 24 and completing the mixture.

It will of course be apparent as the throttle valve opens that the needle valve 44 is also withdrawn from its seat 21 and allows more fluid to flow into the reservoir 18 to promptly replace whatever has been withdrawn by the entering air. The movement of the throttle, therefore, accurately controls the mixture regulating devices and insures at all speeds the most efficient mixture, allowing a sure mechanical control of the fluid without the usual complicated cams, rollers and the like. A further feature resides in the ready adjustment of the air control valve 26 and the needle valves 44 and 46, which can be adjusted without disturbing the throttle, thereby allowing a simple adjustment for slow speed without changing the high speed adjustment.

Particular attention is directed to my novel adjustable air throttle which serves to produce a priming action by directing a quantity of air, during the starting operation, through the fluid in the auxiliary reservoir, thus giving a rich mixture to start the engine. In the event of insufficient closure of air throttle 26 the external auxiliary device can be adjusted to provide the proper mixture for starting and slow speed running. The adjusting nut 37 controlling the throttle valve 30 forms an important feature of my construction, since the air control mechanism rests by gravity on the top thereof and hence any movement of the said nut

to change the adjustment of the throttle has no effect whatsoever on the adjustment of the coöperating adjuncts. Should the throttle be left in any one position and the load suddenly taken off the engine, the increased speed will produce a rapid flow of air through the valve 26 and the equalizer tube 28, as well as through tube 66 of auxiliary device, whereby the fluid in the auxiliary 10 reservoir 18 and in the auxiliary device 60 is lowered considerably and the resulting mixture will consequently become leaner as the flow of gasoline is constant and no suction is produced on openings 19 and 61. With 15 the throttle in the same position and a heavy load thrown on the engine, the decrease in speed thereof will draw less air through the several passages and the fluid will rise in the auxiliary reservoirs, whereby a richer 20 mixture results to take care of the increased load.

The needle valve 46 is so adjusted that when the valve 44 is adjusted for high speed in its relation to the seats 21, the passageway 25 45 will be open about one turn of the thumb screw 47, thereby allowing a further supply of fluid to enter by way of ports 43 when running at slow speed. Of course it will be understood that at high speed this opening 30 is not necessary and in fact would be rendered useless, as the fluid in the auxiliary chamber 18 is at that time below the ports 43, thus not interfering in any way with the high speed adjustment when the throttle is 35 open.

It will be readily appreciated by any one skilled in the art that the combination of the external auxiliary device and the internal equalizer mechanism with a series of adjustments are provided in order to render the range of operation of the engine a very extensive one and to permit a much slower speed on the high speed gearing than can ordinarily be obtained and also to permit an 45 efficient regulation at slow speed. It is to be understood that this external auxiliary device is not limited in its usefulness to the present carburetor but may be attached to any float feed carburetor to insure prompt 50 and easy starting.

In setting the device to produce the best results the external auxiliary mechanism is first adjusted so that the valve 64 will admit the maximum supply of fluid from the 55 reservoir 2 necessary to obtain the correct proportion of air and fluid for slow speed and starting work and then the valve 44 is adjusted in a similar manner to control the inlet 19 so that the necessary supply of fluid 60 enters the auxiliary reservoir 18 to take care of the mixture for high speed running when the throttle is wide open and then the needle valve 46 is adjusted relative to the bore 45 to compensate for slow speed work, 65 the result being that the three differently set

valves so work together as to give substantially perfect control over the mixture at any speed.

It will now be apparent that I have devised a novel and useful construction which 70 embodies the features of advantage enumerated as desirable in the statement of the invention and the above description and while I have in the present instance shown and described the preferred embodiment thereof 75 which has been found in practice to give satisfactory and reliable results, it is to be understood that the same is susceptible of modification in various particulars without departing from the spirit or scope of the invention or sacrificing any of its advantages. 80

Having thus described my invention, what I claim as new and desire to secure by Letters Patent, is:—

1. In a device of the character described, 85 a main reservoir, a mixing chamber adjacent thereto, a fluid inlet to said reservoir, a mixture outlet from said mixing chamber, a throttle valve, an auxiliary reservoir having communication with said main reservoir and 90 said mixing chamber, a main air valve, means to supply a mixture of air and fluid to said mixture outlet when said main air valve is closed and means to simultaneously control said throttle valve and said air valve. 95

2. In a device of the character described, 100 a main reservoir, a mixing chamber adjacent thereto, a fluid inlet for said reservoir, a mixture outlet from said mixing chamber, a throttle valve, an auxiliary reservoir having communication with said main reservoir and 105 said mixing chamber, an air inlet to said auxiliary reservoir, and a port exterior of said throttle valve leading from said auxiliary reservoir to said mixture outlet. 105

3. In a device of the character described, 110 a main reservoir, a mixing chamber adjacent thereto, a fluid inlet for said reservoir, a mixture outlet from said mixing chamber, a throttle valve, an auxiliary reservoir having communication with said main reservoir and 115 said mixing chamber, an air inlet to said auxiliary reservoir, and a port exterior of said throttle valve leading from said auxiliary reservoir to said mixture outlet, the area of said port being less than said air inlet. 115

4. In a device of the character described, 120 a reservoir, a mixing chamber adapted to communicate therewith, a fluid inlet to said reservoir, a mixture outlet from said mixing chamber, an auxiliary reservoir having communication with said main reservoir and 125 said mixing chamber, an air inlet to said auxiliary reservoir and adapted to discharge air beneath the fluid level therein, a main air valve, and a port exterior of said air valve adapted to deliver a supply of air and fluid from said auxiliary reservoir to said mixture outlet. 130

5. In a device of the character described, a main reservoir, a mixing chamber adjacent thereto, an auxiliary reservoir communicating with said mixing chamber, a fluid inlet for said main reservoir, a mixture outlet from said mixing chamber, a fluid inlet from said main reservoir to said auxiliary reservoir, an air inlet for said auxiliary reservoir, a valve controlling said fluid inlet and having a bore therein, and a valve controlling said bore.
10. In a device of the character described, a main reservoir, a mixing chamber adjacent thereto, an auxiliary reservoir communicating with said mixing chamber, a fluid inlet for said main reservoir, a mixture outlet from said mixing chamber, a fluid inlet from said main reservoir to said auxiliary reservoir, a member extending into said auxiliary reservoir and having an air passage therethrough, a throttle valve controlling said mixture outlet, a main air valve mounted on said throttle valve and having an extension forming a continuation of said air passage, 20 and a cap secured to said extension provided with a plurality of openings communicating with said air passage.
15. A carbureter comprising a reservoir, a mixing chamber adjacent thereto having communication therewith, a fluid inlet to said reservoir, a mixture outlet from said mixing chamber, a chamber secured exterior of said carbureter and communicating at one end with said reservoir and at the other end with 25 said mixing chamber, a valve controlling
- the supply of fluid from said reservoir to said chamber, and means to admit air to said chamber to furnish a supply of mixed air and fluid to said mixing chamber.
8. A carbureter comprising a reservoir, a mixing chamber adjacent thereto having communication therewith, a fluid inlet to said reservoir, a mixture outlet from said mixing chamber, a tubular member detachably secured exterior of said carbureter and communicating at one end with said reservoir and at the other end with said mixing chamber, a fluid inlet to said tubular member and a valve mounted on a hollow stem for controlling said fluid inlet, said stem having a plurality of openings therein and positioned beneath the normal fluid level, whereby an auxiliary supply of mixed air and fluid is delivered to said mixing chamber.
15. In a device of the character described, a casing forming a reservoir, a mixing chamber communicating therewith, a fluid inlet to said reservoir, a mixture outlet from said mixing chamber, a tubular member exterior of said casing and communicating with both said reservoir and mixing chamber, a fluid inlet to said tubular member, and means to admit an auxiliary supply of air to said tubular member, whereby a priming mixture is delivered to said mixture outlet.

ALFRED WEILAND.
